WITNESS:

UNITED STATES PATENT OFFICE.

FREDERICK A. WHITE, OF PLEASANTVILLE, PENNSYLVANIA.

WRENCH.

Application filed August 25, 1924. Serial No. 734,099.

To all whom it may concern:

Be it known that I, FREDERICK A. WHITE, a citizen of the United States, residing at Pleasantville, in the county of Venango and State of Pennsylvania, have invented new and useful Improvements in Wrenches, of which the following is a specification.

This invention has reference to tools for handling drill bits or other tools used in drilling or operating artesian wells and has for its primary object to provide a swivel wrench with roller bearings between the head and jaw thereof to eliminate friction as well as to provide the open end of the head with a removable gate in the nature of a segment forming the same with a safety device for preventing the bits falling out of the wrench.

A further object is to simplify and improve the existing art by producing a wrench of this class characteristic of simplicity in construction, cheapness in manufacture and efficiency in operation.

To the attainment of the foregoing and other objects which will present themselves as the nature of the invention is better understood, reference is to be had to the drawings which accompany and which form part of this application.

In the drawings:—

Figure 1 is a top plan view of the wrench.

Figure 2 is a sectional view approximately on the line 2—2 of Figure 1.

Figure 3 is a bottom plan view of the wrench.

Figure 4 is a horizontal sectional view approximately on the line 4—4 of Figure 2.

Figure 5 is a view of the head with the jaw and the ring carried thereby removed.

Figure 6 is a perspective view of the segmental bridge or gate.

The frame of the improvement includes a lever 1 having one end provided with a yoke 2. The yoke, preferably at its juncture with the lever 1 has an eye 3 whereby the frame may be supported, if desired, by a crane or derrick carrying the usual hooked chain to engage in the eye 3.

The arms of the yoke 2 are provided with bearing eyes 4 that receive therethrough removable trunnions 5 secured in the sides of the head 6. The head is in the nature of a ring having an open side,

A flanged ring member 7 is received in the head. A jaw plate 9 is bolted or otherwise removably secured on the ring member 7, the said plate having a substantially rectangular slot or opening 10 therethrough in a line with the opening in the head and in a line with the opening in one side of the ring 7, when these elements are disposed in the position illustrated in Figure 1 of the drawings. The ring 7 thus forms the base or body of the jaw plate, and the said plate 9 being removably secured to its base permits of the arrangement of other plates thereon having different sized openings 10 to engage with different sized bits or other tools. Also between the plate 9 and the head 6 there are preferably arranged anti-frictional roller bearings 11, carried by the plate 9.

The ends of the body have at their inner corners wedge-shaped notches 12. The wedge-shaped notches are designed to receive therein the wedge-shaped ends of a segmental bridge or gate member 14. The bridge is held in position by frictional engagement of the reduced wedge-shaped ends 15 thereof with the walls of the wedge-shaped notches 12 of the ring members 7. The bridge segment 14 is, however, provided with a handle 16 whereby the same may be arranged on or removed from the head. The bridge piece 14 forms an efficient means for preventing tools dropping through the opening in the tool when the wrench is in operation. The ring base proper for the jaw is provided on its underface with the usual outwardly curved handles 17 for the well-known purpose.

It is thought that the foregoing description, when taken in connection with the drawings will fully set forth the construction and advantages of the improvement to those skilled in the art to which it relates.

The rollers 11 space the head 6 from the plate 9 and thereby permits a free passage of air between the head and plate, thereby preventing rust between these parts and also permitting the ready disassociation of the said parts.

Having described the invention, I claim:—

In a wrench, the combination of a yoke frame, a ring head swiveled thereon having an opening in one side thereof and having its

ends provided with wedge notches, a flanged ring member on the lower face of the head and in contact with the inner periphery thereof, said ring member having an opening through one side thereof, a jaw plate having an opening therethrough removably secured to the ring member, roller bearings

between the jaw plate, the ring member and the head, a segmental bridge plate having wedge-shaped ends received in the wedge-shaped notches of the head, and a handle on the bridge plate.

In testimony whereof I affix my signature.

FREDERICK A. WHITE.
